UNITED STATES PATENT OFFICE.

SIMEON BERARD, OF FALL RIVER, MASSACHUSETTS.

SPINNING-FRAME.

SPECIFICATION forming part of Letters Patent No. 622,104, dated March 28, 1899.

Application filed October 6, 1897. Renewed January 12, 1899. Serial No. 702,005. (No model.)

To all whom it may concern:

Be it known that I, SIMEON BERARD, a citizen of the United States, and a resident of Fall River, in the county of Bristol and State of Massachusetts, have invented certain new and useful Improvements in Spinning-Frames; and I do hereby declare that the following is a full, clear, and exact description of the invention, which will enable others skilled in the art to which it appertains to make and use the same, reference being had to the accompanying drawings, which form a part of this specification.

My invention relates to spinning-frames; and its object is to provide improved means for automatically reciprocating or moving the ring-rail up and down, so as to insure the yarn being wound evenly on the bobbins from end to end, and also to provide an improved stop mechanism for automatically stopping the machine when the bobbins are full.

The invention consists in the novel construction and combination of parts hereinafter fully described and claimed.

In the accompanying drawings, Figure 1 is a side elevation of a spinning-frame constructed in accordance with my invention. Fig. 2 is a front elevation of the same. Fig. 3 is a plan view, on an enlarged scale, of the cam-frame, showing the filling and building and stop-motion cams and other parts. Fig. 4 is a detail perspective view of the building and stop-motion cam. Fig. 5 is a similar view of the filling-cam. Fig. 6 is a side view of the slide and feed-cam.

In the said drawings the reference-numeral 1 designates the machine-frame, and 2 the vertically-movable ring-rail, supported by a rod 3, passing through a hole in the horizontal spindle-rail 4. The lower end of this rod is pivotally connected with a lever, hereinafter described, for vertically reciprocating the ring-rail.

The numeral 5 designates the spindles, journaled to the rail 4 and provided with whisks 6, by which they are rotated.

The numeral 7 designates the bobbins on said spindles.

The numeral 8 designates the cam-frame near the bottom of the machine at one end, provided with a horizontal shaft 9, provided at one end with a worm-wheel 10, with which

meshes a worm-gear 12, journaled to the machine-frame and provided with a sprocket-wheel 13. Passing around this sprocket-wheel 55 is a sprocket-chain 14, which also passes around a similar sprocket-wheel 15 at the upper end of the machine, the shaft of which is provided with a cog-wheel 16, driven by a driving-shaft 17 through the medium of pinion 18 and intermediate gears 19 and 20. Mounted on said shaft are a fast pulley 21 and a loose pulley 23.

The numeral 24 designates a laterally-movable shifting device for shifting the belt (not 65 shown) from one pulley to the other.

The shaft 9 is formed with a longitudinal groove 25, with which engages a screw 26 of a cam 27, loosely mounted on said shaft, so as to slide laterally thereon, but rotatable 70 therewith by means of said screw. This cam I term the "filling-cam," as by its action the ring-rail is vertically reciprocated to insure the even winding of the yarn. Engaging with this cam is a pin or dog 28, secured to a slide 75 29, working in a longitudinal slot 30 on the cam-frame and provided with an inclined feed-cam 31. This cam has a depending slide 32, formed with a slot 34, through which passes a set-screw 35, provided with a washer 36. 80 By loosening this screw the said cam can be adjusted. Connected with the said slide is a rope 37, which passes around a pulley 38 at one end of the cam-frame and is secured to the segment-head 39 of a lever 40, the other end 85 of which lever is connected with the rod 3.

Loosely mounted on the shaft 9 is a building and stop-motion cam 41, the cam-face being in the form of a spiral and having a straight longitudinal edge 42, as seen in Fig. 4. This 90 cam engages with a pin 43, having a triangular head 43^a secured to one of the sides of the cam-frame. Secured to said stop-cam is a ratchet 45, with which engages a pawl 46, pivoted to a lever 47, journaled on said shaft 95 9 and provided with a cam-block 48, which works on the feed-cam.

The numeral 49 designates a stop-motion lever pivoted to a lug 49^a, secured to the frame 1, the upper end of which engages with a catch 100 50 on a horizontal rod 51. The lower end of this rod 49 lies in the path of the cam 41, so that as the latter moves back, as hereinabove described, it will strike and actuate the same.

Connected with this catch is a chain 52, having a weight at its lower end which shoots the rod outward when the lever releases the catch, striking the belt-shifter and shifting the belt 5 from the fast to the loose pulley and stopping the machine.

At the beginning of the operation the building and filling cams will be at the left of the frame 8, with the pin 43^a engaging with the 10 front end *a* of the spiral face of cam 41. The machine is now set in motion by actuating the lever 47 by hand, so that the pawl will turn ratchet-wheel 45 sufficient to allow the lower end of rod 49 to clear the end *b* of cam 15 41. The belt is then shifted from the loose to the fast pulley, when the upper end of rod 49 will engage with catch 50, so as to hold the rod which actuates the belt-shifter. The shaft 9 will now be rotated through the 20 medium of the worm and worm-wheel and connections with the driving-shaft. As said shaft rotates, the filling-cam is correspondingly rotated, which, acting on the dog of the slide, will cause the latter to be reciprocated 25 back and forth. The said slide makes one reciprocation for each revolution of and being pushed by the cam toward the worm-wheel during one half of its revolution, and consequently elevating the ring-rail through the 30 rope, lever, and rod, and during the other half of the revolution allowing the slide to be pulled in the opposite direction by the weight of the ring-rail. This reciprocation of the slide is caused by the peculiar formation of 35 the cam. As said slide is pushed forward, as described, the cam on the feed-lever will drop or fall as the feed-cam travels from beneath the same, the pawl thereof traveling over the teeth of the ratchet-wheel; but on the back- 40 ward movement of the slide the feed-cam will elevate the said lever, and the pawl engaging with one of the teeth of the ratchet will turn the same a distance equal to one or more teeth, according to the adjustment of 45 the feed-cam. The building and stop cam will be correspondingly rotated, and the spiral face engaging with the fixed pin 43 will cause the said cam and the filling-cam to be moved forward. This operation will be repeated 50 55 until the bobbins are full, when the building and stop cam will have made a complete revolution. The said cam will now ride off the pin, when the building and stop and filling cams and slide will be returned to normal position by the weight of the ring-rail acting through the medium of the rod connected therewith, the lever, and the chain connected with the slide. As the building and stop cam reaches the end of its backward stroke 60 65 its end will strike and operate the stop-lever, releasing it from the catch of the horizontally-movable rod, which will be projected outwardly to operate the belt-shifter.

From the above it will be seen that the filling-cam makes a revolution with every revolution of the shaft 9, while the building and stop-motion only completes its revolution

when the bobbins are full, the movement of the filling-cam being continuous, while that of the building and stop-motion cam is intermittent.

Having thus fully described my invention, what I claim is—

1. In a spinning-frame, the combination with the vertically-reciprocating ring-rail, the 75 supporting-rod and lever connected therewith, of the slotted cam-frame, the slide working therein, the rope connected with said slide and lever, the pulley over which said rope passes, the pin or dog secured to said slide, 80 the rotatable shaft journaled in said frame and formed with a longitudinal groove, the filling-cam with which the pin on said slide is adapted to engage, the pin passing through said cam and engaging with the groove in the 85 shaft, the worm-wheel secured to said shaft and the connections for driving said wheel, substantially as described.

2. In a spinning-frame, the combination with the cam-frame, the rotatable shaft journaled therein, the rotatable and laterally-movable filling-cam mounted on said shaft, the slide having a pin engaging with said cam, the feed-cam secured thereto and the vertically-movable ring-rail and connections 95 for transmitting motion thereto from said slide, of the spiral building and stop-motion cam mounted on said rotatable shaft, the fixed pin on the cam-frame engaging therewith, the ratchet secured to said building and stop-motion cam, the feed-lever and pawl to actuate 100 said ratchet, the cam-block on said lever adapted to be engaged by said feed-cam and the stop-motion lever and means actuated thereby to actuate the belt-shifter, substantially as described.

3. In a spinning-frame, the combination with the cam-frame, the rotatable shaft journaled therein, the rotatable and laterally-movable filling-cam mounted on said shaft, 110 the slide having a pin engaging with said cam, the feed-cam secured thereto and the vertically-movable ring-rail and connections for transmitting motion thereto from said slide, of the spiral building and stop-motion cam 115 mounted on said rotatable shaft, the pin secured to the cam-frame adapted to engage therewith, the ratchet secured to said building and stop-motion cam, the feed-lever and pawl to actuate 120 said ratchet, the cam-block on said lever adapted to be engaged by said feed-cam, the pivoted stop-motion lever, the horizontally-slidable rod having a catch with which the upper end of said stop-motion lever is adapted to engage, the rope and weight 125 connected with said rod and the horizontally-movable belt-shifter adapted to be operated by said slidable rod, substantially as described.

4. In a spinning-frame, the combination 130 with the cam-frame, the rotatable shaft journaled therein, the rotatable and laterally-movable filling-cam mounted on said shaft, the slotted slide having a pin engaging with

said cam, the slotted feed-cam, the set-screw passing therethrough and through the slide for adjustably connecting said feed-cam with the slide, and the vertically-reciprocating 5 ring-rail and connections for transmitting motion thereto from said slide, of the spiral building and stop-motion cam mounted on said rotatable shaft, the pin secured to the cam-frame and adapted to engage therewith, 10 the ratchet secured to said building and stop-motion cam, the feed-lever and pawl to actuate said ratchet, the cam-block on said lever adapted to be engaged by said feed-cam and the stop-motion lever and means actuated 15 thereby to actuate the belt-shifter, substantially as described.

5. In a spinning-frame, the combination with the rotary and laterally-movable filling-cam, and the intermittently-rotating and laterally-movable building and stop-motion cam 20 and the connections, for vertically reciprocating the ring-rail, and automatically shifting the belt to stop the machine when the bobbins are full, substantially as described.

In testimony that I claim the foregoing as 25 my own I have hereunto affixed my signature in presence of two witnesses.

SIMEON BERARD.
